CARBURETOR METERING CONTROL

Sim V. Clananan, St. Louis, Mo., assignor to Carter Carburetor Corporation, St. Louis, Mo., a corporation of Delaware

Application September 12, 1945, Serial No. 615,817

1 Claim. (Cl. 261—51)

1

This invention relates to carburetors for internal combustion engines and consists particularly in novel means for controlling the motion of the fuel metering device.

In a Patent No. 2,329,748 assigned to applicant's assignee, there is illustrated a suction operated metering pin which extends through the bowl cover and is supported and operated by a parallel link also extending through the bowl cover and itself operated by a suction piston and counteracting spring. This link is provided with a laterally offset arm and a throttle operated element is in position to act upon this arm to move the link and metering pin coincident with throttle movement. An elongated guide is provided for the link in the bowl cover. The cantilever action of the throttle actuator upon the link is such that there is a tendency for the link to tilt in its guide causing excessive wear of the guide and link and, frequently, causing the link to stick rendering the metering device inoperative.

This arrangement also has a spring wire bearing against the upper extremity of the link for assisting in controlling the same. This wire bears upon a flat surface of the link so that its force is effective only in the longitudinal direction.

It is an object of the present invention to provide means for counteracting the cantilever action of the link above described and, consequently, to reduce or avoid excessive wear in the guide and the danger of sticking.

A more detailed object is to arrange the control spring last mentioned and, particularly, in connection with the link so that the force of this spring is applied in a direction to counteract the cantilever action.

In the accompanying drawing, Fig. 1 is a side view, partially sectioned, illustrating a carburetor having the invention applied thereto.

Fig. 2 is a view of a part of the structure in Fig. 1, but with the part in a different position.

The carburetor illustrated has a downdraft mixture conduit 5 provided with the usual fuel bowl 6 having a cover 7. The discharge of mixture is controlled by a throttle valve 8 mounted on a shaft 9. An arm 10 rigid with the shaft is connected by a link 11 to a lever 12 pivoted on a counter-shaft 13 mounted above the bowl cover. At its right hand end, lever 12 is connected by a link 14 to accelerating pump piston rod 15. Lever 12 is shown as of the split type having two parts constantly urged toward their aligned normal positions, as shown, by a tension spring 16.

2

Located in the fuel bowl is the main metering orifice element 18 controlled by a metering pin 19 extending through the bowl cover. This pin is carried by a goose neck link 20 operating in an elongated guide 36 and having a laterally offset arm 21, connected to the metering pin, and with a laterally extending part 22. Link 20 at its lower end is pinned to a piston 23 which works in a cylinder 24 connected by a passage, shown in part at 25, to the carburetor mixture conduit posterior to the throttle. The piston is constantly urged upwardly by a coiled compression spring 26, the arrangement being such that when the intake manifold suction exceeds a certain value, link 20 and the metering pin are drawn downwardly against spring 26.

A pintle 28 anchored in a slot 29 in lever 12 lies beneath link extension 22 so as to urge the link and metering pin upwardly when lever 12 is rotated clockwise as the throttle is opened. A coiled spring 30 wound about a boss 31 on the lever has one end hooked over the lever, as at 32, and its other, elongated end 33 seated in a recess 34 in the upper portion of link 20. The recess is defined by at least one angular wall extending longitudinally of said link and the spring hook normally seats against and engages this wall. In this arrangement, pintle 28 and spring 33 cooperate to eliminate the suction actuation of the metering pin. However, as explained in the above mentioned patent, pintle 28 and spring 33 may be adjusted to allow suction and/or manual control of the pin in various ways.

35 With the pintle and spring 33 disposed as shown, the pintle, during opening movement of the throttle, applies longitudinal, as well as tilting force to link 20 through cantilever extension 22. The tendency of this tilting action would be to cause excessive wear in elongated longitudinal guide 36 provided for link 20 in the bowl cover. In order to counteract such tilting or wedging action, spring wire 33 is seated in the recess 34 so that during longitudinal movement of link 20, the torsional force of this spring is applied longitudinally and the restraining force of the wire is applied against the shoulder forming edge of recess 34 laterally in the direction opposite to the tilting force of pintle 28 so as to counteract this tilting force. Thus, the canting of the link in its guide is eliminated. The excessive wear and sticking of the link, mentioned above, is, accordingly, avoided.

The invention may be modified as will occur to those skilled in the art and the exclusive use

of all modifications as come within the scope of the appended claim is contemplated.

I claim:

In a carburetor, a fuel bowl and a cover therefor, a fuel metering device comprising a metering pin and a control link therefor projecting through the bowl cover, said link including an elongated member having a laterally offset arm formed at its upper end, the upper end of said link being formed with a longitudinally extending angular face, a guideway for said link, said guideway limiting the same to longitudinal sliding movement, a mechanical actuator disposed to act upon said arm for moving the same and said metering pin longitudinally, and a control 15 spring anchored at one end laterally of said link

and extending along said arm, the free end of said spring bearing resiliently against said angular face so as to resist longitudinal movement of said link and restrain tilting forces applied to the arm and link by said actuator.
